FIG. 1

FIG. 2

FIG. 3

FIG. 4

John Van Brunt INVENTOR.

Bartlett & Worcester ATTORNEYS.

UNITED STATES PATENT OFFICE.

JOHN VAN BRUNT, OF NEW YORK, N. Y., ASSIGNOR TO COMBUSTION ENGINEERING CORPORATION, OF NEW YORK, N. Y., A CORPORATION OF NEW YORK.

MECHANICAL STOKER.

1,309,344.

Specification of Letters Patent.

Patented July 8, 1919.

Application filed May 21, 1918. Serial No. 235,797.

To all whom it may concern:

Be it known that I, JOHN VAN BRUNT, a citizen of the United States, residing at city, county, and State of New York, have 5 invented a certain new and useful Improvement in Mechanical Stokers, of which the following is a full, clear, and exact description.

My invention relates to mechanical stokers 10 and has for its object to provide a stoker having a plunger and operating piston located in different horizontal planes and substantially free from side thrusts while in action. It further has for its object to 15 provide means for actuating rocker-bars through counter-shafts for moving the grates so that the piston is substantially free from side thrusts although in a different plane from the rocking-bars. It further has for its object to provide means for 20 adjusting the limits of throw of the grate-bars and also the extent of their movements.

The following is a description of an embodiment of my invention, reference being 25 had to the accompanying drawing, in which,

Figure 1 shows in section, on the line 1—1 Fig. 4, a stoker embodying my invention;

Fig. 2 shows a side elevation of the left-hand end of the stoker;

Fig. 3 shows a partial end view and a partial section on the line 3—3 Fig. 4; and

Fig. 4 is a partial plan view and a partial section on the line 4—4, Fig. 2.

Referring more particularly to the drawings, 1, 1 are series of grate-bars, the alternate bars of each series being reciprocated by rocking-bars 2 as in U. S. Patent No. 818,010 granted to W. R. Wood, Apr. 17, 1906. 3 is a fuel hopper. 4 is a plunger 40 for feeding fuel from the hopper to the retort 5, having the usual movable bottom 6 and fixed plate 7. The movable plate 6 is provided with an upwardly projecting lug 8, which is housed within the plunger 4 and 45 rigidly secured thereto so as to move it over the fixed plate 7. This fixed plate is provided with a slot 9 in which the lug 8 moves to and fro. Pivoted to the lug 8 and extending forwardly therefrom are links 50 10, which are connected to the upper end of a lever 11, extending upward through the enlarged front end of the slot 9 and fulcrumed at 12. The lower end of the lever 11 is within a box 13 carried by the piston rod 14 of the piston 15, which plays within

the cylinder 16. As the piston reciprocates the lever 11 is oscillated and moves the plunger 4 to and fro so as to feed the fuel from the hopper to the retort. The lower end of the lever 11 being in line with the 60 axis of the piston rod, and the upper end being in line with the axis of the plunger 4, the thrusts upon the piston rod and plunger are direct thrusts, so that the side thrusts that would be present if the piston 65 rod and plunger were rigidly connected are avoided.

In order to operate the rocker-arms I provide the head upon the piston rod with two screw bearings 17, 17 and provide two suitably mounted counter-shafts 18, 18, terminating in screws 19, 19, which engage the screw bearings. As the piston reciprocates, the screw bearings cause the screws and counter-shafts to oscillate. Since the screw 75 bearings are symmetrically located on diametrically opposite sides of the axis of the piston their thrusts are counterbalanced so that the resultant thrust upon the piston rod is a direct thrust. 80

In order to communicate the movements of the counter-shafts 18, 18 to the rocking-bars 2, 2, I provide each counter-shaft with a crank-arm 20 and each rocking-bar with a crank-arm 21 and connect each crank 85 arm 20 with a crank-arm 21 by a turnbuckle 22. The crank-arms 20 and 21 are each provided with a plurality of holes 23, 24 so that the turn-buckles can be connected to the several crank-arms at different points which will result in a variation in the throw of the movable grate-bars to any given movement of the counter-shafts 18. By adjusting the turnbuckles 22, however, the relation of the inner ends 95 of the movable grate-bars to the edges of the retort for any position of the counter-shafts 18 can be modified.

In operation, the piston 15 with its piston rod 14 is reciprocated by any suitable fluid 100 pressure so as to move the piston head containing the box 13 and bearings 17. A rearward movement of the piston rod 14 on account of the connections through the lever 11, results in a forward movement of 105 the plunger 4, feeding fuel from the hopper 3 to the retort 5. At the same time, the movement of the screw-bearings 17 causes the counter-shafts 18 to rock, which rocking motion is transmitted through the 110

crank-arms 20 and 21 to the rocking-bars 22, causing the movable grate-bars 1 to move. A reverse movement of the piston rod produces reverse movements of the 5 plunger and grate-bars. As before pointed out, the thrusts on the piston rod 14 in operating the plunger 4 and counter-shafts 18 are so balanced as to avoid side thrusts, the piston head having the bearings for 10 the connecting devices arranged symmetrically relating to the axis of said piston and its rod, and, moreover, through the connections 22 and crank-arms 20 and 21, the throw of the grate-bars can be altered and 15 their position when in rest adjusted.

As will be evident to those skilled in the art, my invention permits of various modifications without departing from the spirit thereof or the scope of the appended claims.

20. What I claim is:

1. In a mechanical stoker, the combination of a retort, movable grate-bars extending from both sides thereof, rocking-bars for moving said grate-bars, a piston and 25 piston rod located in a plane below the plane of said rocking-bars, counter-shafts in the horizontal plane of said piston and on opposite sides thereof, means carried by said piston rod for oscillating said counter-shaft as said piston rod reciprocates, crank-arms upon said counter-shafts and rocking-bars, and means for connecting those crank-arms located on the same side of said piston rod.

30. 2. In a mechanical stoker, the combination of a retort, movable grate-bars extending from both sides thereof, rocking-bars for moving said grate-bars, a piston and piston rod located in a plane below the 35 plane of said rocking-bars, counter-shafts in

the horizontal plane of said piston and on opposite sides thereof, means carried by said piston rod for oscillating said counter-shaft as said piston rod reciprocates, crank-arms upon said counter-shafts and rocking-bars, and means for connecting those crank arms located on the same side of said piston rod, said connecting means being adjustable in length. 45

3. In a mechanical stoker, the combination of a retort, movable grate-bars extending from both sides thereof, rocking-bars for moving said grate-bars, a piston and piston rod located in a plane below the plane of said rocking-bars, counter-shafts in the horizontal plane of said piston and on opposite sides thereof, means carried by said piston rod for oscillating said counter-shaft as said piston rod reciprocates, crank-arms upon said counter-shafts and rocking-bars, and means for connecting those crank-arms located on the same side of said piston rod, said connecting means being adjustable laterally relatively to said crank-arms. 55

4. In a mechanical stoker, the combination of a retort, movable grate-bars extending from both sides thereof, rocking-bars for moving said grate-bars, a piston and a piston rod located in a plane below the plane of said rocking-bars, counter-shafts in the 60 horizontal plane of said piston and on opposite sides thereof, a screw carried by said counter-shafts and screw bearings carried by the end of said piston and engaging with said screws to turn said counter-shafts, 65 crank arms upon said counter-shafts and rocking-bars, and means for connecting those crank arms located on the same side of said piston rod. 70

JOHN VAN BRUNT.
